Application November 30, 1935, Serial No. 59,839

Term of patent 7 years

To all whom it may concern:

Be it known that I, Maurice Handman, a citizen of the United States and residing at Providence, in the county of Providence and State of Rhode Island, have invented a new, original, and ornamental Design for a Brooch Pin or Similar Article, of which the following is a specification, reference being had to the accompanying drawing, forming part thereof, and in which—

Fig. 1 is a front view of a brooch pin showing my new design;

Fig. 2 is a top view upon the line 2—2 of Fig. 1, and

Fig. 3 is a side view upon the line 3—3 of Fig. 1. The design consists of a bar-like parallelogram with vertical sides.

As shown in the drawing this parallelogram is superimposed upon a square with the upper and lower outside lines of the parallelogram extending to and terminating at the outside lines of the square.

The name shown in dotted lines is merely illustrative, it being understood that other names may be used without departing from the spirit of my invention.

I claim:

The ornamental design for a brooch pin or similar article, substantially as shown and described.

MAURICE HANDMAN.
